UNITED STATES PATENT OFFICE.

STERLING ELLIOTT, OF NEWTON, MASSACHUSETTS.

APPARATUS FOR WATERPROOFING SIZED SHEETS.

1,230,068.

Specification of Letters Patent. Patented June 12, 1917.

Application filed December 28, 1914. Serial No. 879,282.

To all whom it may concern:

Be it known that I, STERLING ELLIOTT, a citizen of the United States, residing at Newton, in the county of Middlesex and State of Massachusetts, have invented an Improvement in Apparatus for Waterproofing Sized Sheets, of which the following is a specification.

This invention relates to an apparatus for 10 treating sized sheet material such as paper-sheets for rendering the same waterproof. While having other and more general fields of usefulness, the invention is well adapted for waterproofing thin delicate sheets of 15 paper such as are used for stencil-sheets.

According to the invention, the sized sheets held on suitable supporting-frames, are exposed to the action of formaldehyde gas in a closed housing for a substantial 20 period of time, thereby modifying the sizing to impart a waterproof quality thereto.

Before removing the sheets from the confined housing, they are deodorized, at least to such an extent that the odor therefrom 25 will not be obnoxious; and, according to my invention, this result may be accomplished by displacing the formaldehyde gas with air, although the process may be accelerated by generating in, or introducing into the 30 housing, another gas or fume, such, for instance, as the fume of alcohol or ammonia. The displacement or removal of the formaldehyde gas is not only a desirable, but a necessary step, in order that the housing 35 may be cleared to permit a person to enter and remove the treated sheets and place new sheets in position for treatment; an operation which would be probably fatal unless the formaldehyde gas was, to a large 40 extent, removed. The formaldehyde gas may be generated by placing in the confined housing, a quantity of formaldehyde-containing substance and then releasing the gas, and, in order that a predetermined 45 quantity may be liberated, it is herein proposed to provide a relatively small container adapted to receive a predetermined quantity of the formaldehyde-containing substance, which is sufficient for a single charge, and 50 then permit the entire substance to yield its gas. The invention will be more fully understood from the following detail description taken in connection with the accompanying drawings.

55 Referring to the drawings:—

Figure 1 shows in side elevation, an ap-

paratus constructed in accordance with my invention and adapted for carrying out the method thereof.

Fig. 2 is an intermediate vertical section. 60

Fig. 3 is a fragmentary elevation showing the lower portion of the apparatus at a side opposite that shown in Fig. 1.

Fig. 4 is a vertical section on line 4—4 of Fig. 2. 65

Fig. 5 is a fragmentary view in section on line 5—5 of Fig. 4; and,

Fig. 6 is a fragmentary elevation showing the electric switch control.

A housing adapted to receive a plurality 70 of paper sheets and to be tightly closed, thus to form a confined chamber, is indicated generally at 10, this preferably consisting of a skeleton structural frame-work indicated at 11, arranged with panes of glass 12, at the 75 sides thereof to permit convenient inspection of the contents and having its top and bottom closed by other suitable structural sheet or plate material 13. This housing is provided at its front with two doors 14, 15, 80 which are shown as arranged to close the entire front, said doors being hinged at opposite sides of the housing, as seen at 16, and having adjacent hand-holds 17 for opening and closing them. These doors are adapted 85 to be clamped tightly in closed position to prevent the escape of the gases or fumes by clamp-bolts 18, pivoted at 19 to the framework and equipped with nuts 20, adapted for hand-turning and engaging lugs 21 on 90 the doors. These doors are also equipped with glass panes 12'.

The paper sheets S, to be treated are shown as suspended from suitable frames 22, these frames being of a type adapted to 95 hold a large number of sized sheets properly spaced apart. These sheet-holding frames, loaded with sized sheets to be treated, are adapted to be put into the housing and to rest on shelves or ledges 23 therein, these 100 shelves being suitably spaced to permit the maximum number of frames to be arranged in the housing.

At the bottom of the housing, I place a small kettle or pot 24, having suitable heating-means, here shown as an electric-heater 25, associated therewith and adapted to receive electric energy from a circuit having a switch 26.

At a convenient point, shown as on the 110 outside of the housing, I arrange a small tank 27, and from said tank, a pipe 28 ex-

tends through the wall of the housing and terminates at the container 24, to deliver the contents thereof to the container, and said pipe has a controller-valve 29. This 5 tank is adapted to receive a small predetermined quantity of a liquid which is to be delivered to the kettle or pot.

I also preferably arrange an electric-lamp 31, operated from a circuit 32, just above 10 the container 24, so that the contents thereof can be better kept under observation, and I shield this lamp with guard-plates 33, at each side thereof.

At a convenient point, shown as on the 15 side of the housing, is mounted suitable switch-mechanism, indicated at 34, adapted to control the current supply from leads 35, so that it may be directed for heating the container 24, or operating the blower, and 20 operating the lamp, at will.

Adjacent the bottom of this housing, I mount a series, shown as six of large horizontally disposed pipes 36, having perforations 37, therethrough, opening downward 25 into the housing. These pipes extend from front to back of the housing and their ends are opened to the atmosphere except as closed by the slide-valves to be now described.

These valves consist of opposite slides 38, 30 39, fitted to slide-ways 40, at the bottoms of the two doors. These slides have passages 41, therethrough, registering in one position with the pipes, while the slides in another 35 position close the pipes, the right hand slide in Fig. 1 being shown in pipe-closing position, and the left-hand slide in open position. At the back of the housing a single slide 42, is fitted in slide-ways 43, and extended across the entire back which is adapted to control 40 all of the pipes, it having a series of passages 44 adapted to register with the pipe-openings 45, when the slide is moved to the right from the position shown in Fig. 3. For conveniently operating this slide it may 45 be connected by a pivoted link 46, and rock-arm 47, with a shaft 48 journaled in the base and extending to the front of the housing, with an operating-arm 49 at the front, arranged conveniently for the operator.

Extending across the housing, adjacent the top thereof, but spaced therefrom, is fixed a horizontal perforated plate 50, the 55 perforations 51, through this plate, being preferably of a combined area, substantially equal to that of the perforations 37, so that no violent draft or strong air-current can be created through the housing. This causes the air to be equally distributed over the entire space so that all sheets of paper will be 60 equally affected. The top of the housing has connected thereto a pipe 52, leading to a blower 53, which may be electrically operated, and controlled by a circuit having a switch 54, whereby there is created a suction 65 up through the housing. This pipe may be

controlled by a damper-valve 55, which is preferably elongated so as to lie lengthwise of the pipe to a substantial extent when closed, as shown, having flexible end-portions 56 adapted to press against the pipe-sides and effect a more complete closure. This damper may be operated by any usual form of link and rod connection 57.

In use, and in carrying out the method of the present invention, the housing is filled with the paper sheets arranged on the series of frames 22, these sheets being coated and impregnated with glue or like suitable sizing material. The pot 24 has placed therein a quantity of substance adapted, when heated, 70 to liberate and give off a gas, such as formaldehyde gas; for this purpose, the liquid commercially known as "formalin" is suitable, and for a housing of convenient workable size such as that shown, a charge of 80 about seven ounces of formalin is requisite.

The slide-valves 38, 39, 42 being closed and also the damper 55, and the doors being clamped tight by the clamp-nuts 20, heating-current is applied to the pot 24, and the 85 newly liberated formaldehyde gas is given off to fill the housing and act on the sized paper. This action is allowed to continue for a substantial period of time, in practice usually about three hours, during which 90 time, the contents of the pot 24, gradually evaporates and finally disappears entirely. The sizing in the paper is, during this time, 95 acted on and modified by the newly liberated formaldehyde rendering it waterproof and tough. Thereupon the slides 38, 39, 42, are moved to open the pipes 36, and the current turned on to operate the blower 53. This causes a rapid circulation of air up through the housing to clear out the formaldehyde 100 fumes, this circulation being, however, restrained from too great violence or any considerable blowing action by the disposition of the inlet pipe apertures 37, which open downward away from the direction of the 105 draft and away from the paper sheets in the housing; further, since, as noted, the exhaust apertures 51 are only of about the same total area as the inlet apertures 37, there can be 110 no appreciable draft through the relatively large space of the housing. When the element of time is not important, this air circulation may be relied on to displace the formaldehyde fumes without any other agency, merely by giving sufficient time for 115 the displacing operation to continue, so that the remaining fumes will not be too obnoxious. When it is desired to expedite the operation however, and to run the apparatus at full capacity, I preferably, at the same 120 time that the displacing operation by the blower is going on, or after said operation has continued for a short period of time, deliver a quantity of a suitable volatile liquid, such as alcohol, or, if preferred, am-

monia, into the heated pot 24, by opening the valve 29 from the container 27 of this liquid, which is adapted to receive a small predetermined quantity of said liquid. The 5 fumes of such volatile liquid quickly modify, and to a large extent, displace the formaldehyde fumes; thus in a relatively short time, the obnoxious character of the fumes remaining in the housing is done away with, 10 so that the housing may be opened and the treated paper taken out, and a new charge placed therein. I preferably provide the pot 24 of a size just large enough to receive the requisite charge for treating one supply 15 of paper and by keeping this under observation, as permitted and facilitated by the lamp 31, it can be readily determined when the generation of formaldehyde gas ceases, so that by using the instrumentalities set 20 forth for clearing out the noxious and deadly fumes, all danger therefrom is avoided.

I am aware that the invention may be embodied in other specific forms without departing from the spirit of essential attributes 25 thereof, and I therefore desire the present embodiment to be considered as illustrative and not restrictive.

I claim:—

1. Apparatus of the kind described, comprising a housing adapted to receive and hold suspended a plurality of sized sheets, and to be tightly closed to produce a confined chamber, means for liberating a quantity of formaldehyde gas in said chamber, 30 and means for causing a mild circulation of air to said chamber consisting of a blower having a connection through restricted openings, spaced apart about the top of said chamber, and a series of pipes extended 35 across said chamber adjacent the bottom, opening at their ends to the atmosphere, and having correspondingly restricted openings spaced apart throughout their length, means 40 for closing said pipe, and means for closing 45 said blower connection at will, substantially as described.

2. Apparatus of the kind described, com-

prising a housing adapted to receive and hold suspended a plurality of sized sheets, and to be tightly closed to produce a confined chamber, means for liberating a quantity of formaldehyde gas in said chamber, 50 and means for causing a mild circulation of air through said chamber, consisting of a blower having a connection through restricted openings spaced apart, about one side of said chamber, and a series of pipes extending across said chamber adjacent an opposite side thereof with correspondingly restricted openings facing toward the adjacent side, 55 means for closing said pipes, and means for closing said blower connection at will, substantially as described.

3. Apparatus of the kind described, comprising a chamber adapted to receive a plurality of sheets to be treated and to be tightly closed, a relatively small container having provision to be heated and placed within the chamber so as to give off gaseous vapor into said chamber when the contents thereof 70 is heated, and means arranged outside of the chamber and extended thereinto for delivering a predetermined quantity of a volatile liquid to said container, substantially as described. 75

4. Apparatus of the kind described, comprising a chamber adapted to receive a plurality of sheets to be treated and to be tightly closed, a relatively small container having provision to be heated and placed within the 80 chamber so as to give off gaseous vapor into said chamber when the contents thereof is heated, and means arranged outside of the chamber and extended thereinto for delivering a predetermined quantity of a volatile 85 liquid to said container, said means including a closing valve.

In testimony whereof, I have signed my name to this specification, in the presence of two subscribing witnesses.

STERLING ELLIOTT.
